GEORGE A. SEIB, OF ILION, NEW YORK, ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,118,065.

Specification of Letters Patent. Patented Nov. 24, 1914.

Application filed December 8, 1909. Serial No. 532,097.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My invention relates to typewriting machines and more particularly to means for effecting a series of intermittent operations of a type carrier to produce a line of hyphens or other characters.

It is particularly desirable in producing 15 tabulating work or in making out bills, for instance, to employ leader lines to connect, say, the designation of the goods purchased, which is usually located near one side of the sheet, with the amount of the purchase at 20 the other side of the sheet. Thus:—

7 bales of hay	-----	\$35.00
4 bushels of corn	-----	2.00

Ordinarily, where for example a tabulator is employed, it would be necessary to write the designation of the goods, then tabulate to bring the carriage to the proper denominational position to write the amount. If a leader line is to be used it would be inserted after the amount has been written by first moving the carriage back to position by hand where the first hyphen, star or other character employed for the leader line would appear, say, after the word "Hay." 30 The operator would then continue to write the hyphen, depressing the hyphen key for each imprint until the previously written amount "\$35.00" is nearly reached, care being exercised not to carry the hyphens into 35 the amount written. Or the operator, after writing the item, may write the line of hyphens up to a given point, say, 60, on the scale and then operate the decimal tabulator so as to bring the carriage to proper 40 position for the writing of the amount. Producing the leader lines in either of these ways is slow and tedious and requires close 45 attention on the part of the operator to avoid mistakes in inserting the leader lines 50 after the items are written.

One of the main objects of my invention is to overcome the above and other difficulties and to provide simple and efficient means for producing a line of characters by

intermittently actuating the type carrier 55 during a continuous run of the carriage.

A further object of my invention is to provide means to automatically actuate the type carrier during the travel of the carriage under control of the tabulator, so that 60 a leader line may be automatically printed, to connect two designations at opposite sides of the sheet, during the travel of the carriage, effected by an actuation of the tabulator.

To the above and other ends which will hereinafter appear, my invention consists in the features of construction, arrangements of parts and combinations of devices to be hereinafter described and particularly 70 pointed out in the appended claims.

In the accompanying drawings, wherein like reference characters indicate corresponding parts in the various views, Figure 1 is a fragmentary, vertical, fore and aft 75 sectional view of one form of typewriting machine embodying my invention. Fig. 2 is a fragmentary plan view showing some of the parts illustrated in Fig. 1. Fig. 3 is a fragmentary front elevation showing 80 the type bar carrying the hyphen type and some of the associated parts. Fig. 4 is an enlarged detail fragmentary sectional view showing a portion of the mechanism by which the hyphen type bar is intermittently 85 actuated. Fig. 5 is a fragmentary plan view of the same.

I have shown my invention in the present instance embodied in a front-strike machine similar to the No. 11 Remington machine, although some of the parts are omitted and some are only conventionally represented, but it should be understood that the invention may be embodied in various styles of typewriting machines and 90 that the invention from certain aspects is not restricted to a front-strike machine.

The frame of the machine comprises a base 1, corner posts 2 and a top plate 3. Key levers 4 having keys 4^a are fulcrumed 100 upon a bar 5 and the key levers and the parts controlled thereby are restored to normal position by springs 6 connected to the key levers. To each key lever is connected a link 7, the upper end of the link being 105 pivoted to a sub-lever 8 which in turn is pivoted to a link 9 connected to a type bar 10. The segmentally arranged type bars

are or may be pivoted as in the No. 11 Remington machine to strike upwardly and rearwardly against the front face of a cylindrical platen 11. I have shown but one type 5 action, that being the one which controls the type carrying the hyphen mark.

A carriage 12 is mounted on anti-friction rollers 13 to move from side to side of the machine over the top plate, the platen 11 being supported in any suitable manner by 10 the carriage. Arms 14 are pivoted at 15 to upwardly extending lugs 16 on the carriage. The arms 14 extend rearwardly and are connected to a feed rack 17 which 15 meshes with a feed pinion 18 connected to suitable escapement devices (not shown) in the usual manner. A spring drum 19 is connected by a band 20 to the carriage to move the carriage in the direction of its 20 feed. Rearwardly extending arms 21 are secured to the carriage and support a column stop bar 22 at the rear ends thereof. Column or tabulator stops 23 are adjustable to different positions along the stop 25 bar 22 in the usual manner and are adapted to coöperate with denominational stops 24 which are received in and work through openings in a rigid guide 25 secured to the top plate of the machine by screws 26. The 30 denominational stops form part of upwardly extending arms 27 of angular levers pivoted in the base of the machine on a pivot rod 28. The forwardly extending arms 29 of the tabulator levers are arranged beneath the key levers 4 and are provided with tabulator keys 30 by which the denominational stops are projected forwardly to coöperate with the column stops 23 on the carriage. Springs 30^a return the 35 tabulator key levers and the stops carried thereby to normal position. It should be understood that for the purpose of the present invention any suitable tabulating mechanism may be employed.

45 A universal bar 31 is carried by and rigidly connects two arms 32 pivoted on a rod 33 carried by the base of the machine. The universal bar 31 is situated beneath the forwardly extending arms 29 of the tabulator 50 key levers to be actuated thereby, the universal bar, however, being unaffected by the actuation of the printing keys. An arm 34 extends rearwardly from the universal bar 31 and is pivotally connected to an upwardly extending link 35 pivoted at 55 its upper end to a rearwardly extending arm 36. The arm 36 constitutes part of a frame 37 pivoted at 38 to upwardly projecting lugs or ears 39 formed on a bracket 60 plate 40 secured to the top plate of the machine by a screw 41. The frame 37 is thus pivoted to turn on an axis which is parallel to the axis of the platen. The frame 37 is connected with and carries a bearing sleeve 65 42 which receives a shaft 43. The forward

end of this shaft has what may be termed a disengaging pinion 44 fixed thereto; and the rear end of the shaft carries a bevel pinion 45 secured to the shaft by a set screw 46 which is received in a tapped opening 70 in the hub of the bevel pinion and bears at its inner end against the shaft 43. It will be seen therefore that the bevel pinion 45, shaft 43 and the pinion 44 are all fixed to turn together on the bearing 42 connected 75 with or formed as a part of the pivoted frame 37 and that these parts are adapted to swing when the pivoted frame turns on its pivot 38. In the normal positions of the parts the pinion 44 extends beneath and is 80 out of mesh with the feed rack 17. When, however, a tabulator key 30 is depressed, the universal bar 31 will likewise be depressed to pull down on the arm 36 through the intermediate link 35. The effect of this 85 movement is to elevate the pinion 44 to throw it into mesh with the teeth of the feed rack and to lift the feed rack out of engagement with the feed pinion 18 of the escapement mechanism. This results in 90 freeing the carriage from control of the escapement mechanism at the actuation of a tabulator key and in throwing the pinion 44 into mesh with the feed rack to be turned thereby during the travel of the carriage in 95 tabulating operations. When the depressed tabulator key is released a spring 31^a returns the universal bar and the parts controlled thereby to normal positions shown in Fig. 1.

100 A bearing sleeve 47 is secured to the under side of the top plate and constitutes a support for a vertically disposed shaft 48 which extends through an opening in the top plate. The upper end of this shaft 105 48 has a bevel pinion 49 secured thereto by a screw 50 which is threaded into a tapped opening in the hub of the bevel gear 49 and bears at its inner end against the shaft 48 to rigidly connect the bevel gear to the 110 shaft. The lower end of the hub of the bevel gear 49 bears against the upper side of the top plate and supports the shaft 48 and the parts carried thereby in position. The lower end of the shaft 48 has a cam 115 wheel 51 secured thereto by a screw 52 which is threaded into a tapped opening in the hub of the cam wheel and bears at its inner end against the shaft. The cam wheel in the present instance is in the nature of a seven-point wheel which forms a sinuous cam on the periphery thereof. The contact face of this cam coöperates with two anti-friction rollers 53 and 54 carried by shouldered headed screws 55 received at 120 their threaded ends in tapped openings in a reciprocating actuating device 56 which is in the nature of a rod or bar that extends fore and aft of the machine and is flattened at its rear end 57 where the rollers 53 and 125 54 are secured to the device 56. The device 56 is actuated by a cam 58 secured to the cam wheel 51 and is caused to move back and forth by a cam 59 secured to the 130 shaft 48.

54 are connected thereto. The anti-friction rollers are situated on opposite sides of the axis of the cam wheel 51 as indicated in Figs. 4 and 5, and the construction is such that each roller will successively co-act with a high portion of a tooth of the cam wheel and with an interdental space between the teeth. The effect of this construction is to transmit a longitudinal reciprocating motion to the actuating device or rod 56 when the rotative device or cam 51 is turned. The part 57 of the rod has a slot 56^a extending longitudinally thereof and in which the lower end of the shaft 48 is received to 15 guide the rear end of the rod in its reciprocating movements. A washer 56^b is held in place by a headed screw 56^c received in a tapped opening in the lower end of the shaft 48 to support the rear end of the rod. 20 The forward end of the rod 56 passes through an opening in a plate 57^a attached to the frame of the machine to guide and support the rod at its forward end. The rod 56 is tapped at its front end to receive 25 a headed screw 58 which constitutes a contact for coöperation with the type bar 10 carrying the hyphen, or other suitable character, when the type bar is at or near the printing point. When the head of the screw 30 is unduly worn, the screw may be removed and a new one substituted therefor.

It will be understood that the position of the bevel gear 49 is such that when the arm 36 is lowered through the actuation of a 35 tabulator key, the bevel gear 45 will be thrown into mesh with the companion bevel gear 49 at about the time that the pinion 44 is thrown into mesh with the feed rack and releases it from engagement with the feed 40 pinion. The effect therefore is to operatively connect the rotative device or cam 51 with the carriage when it is released from its escapement mechanism and is under control of the tabulator, so that during the free 45 run of the carriage the cam 51 will be rotated to produce a reciprocating longitudinal movement of the bar 56 and if at this time pressure is maintained on the key of the type bar carrying the hyphen or other 50 suitable character, the type bar will be given a vibratory movement through the contact of the reciprocating bar 56 therewith. This effects intermittent printing movements of the type bar to produce a 55 line of hyphens corresponding in length to the travel of the carriage during the tabulating operation. When the carriage is arrested by the coöperation of the tabulating stops the cam 51 will cease to rotate and the 60 intermittent printing movements of the type bar will cease. Pressure on the printing key is then released and when the tabulator key is released the parts will be restored to normal positions shown in Fig. 1 65 to lower the feed rack into engagement with

the feed pinion and to disconnect the pinion 44 from the feed rack, thus breaking the operative connection between the carriage and the means for effecting the intermittent printing movements of the type bar. The 70 projected tabular stop will be withdrawn when pressure on the tabulator key is released and the operator may proceed to fill in the amount.

It will be seen that by this mechanism the 75 operator need exercise no care in effecting the printing of the leader lines connecting the first part of a written line with the last part thereof, this being automatically effected by the tabulating operation when pressure is maintained on the hyphen key. When the operator desires to tabulate without employing leader lines it is merely necessary to refrain from depressing the hyphen key and the automatically operating 80 actuating device will be inoperative to move the type bar.

It will also be understood that the devices by which the hyphen type bar is intermittently actuated, by the power employed 90 to move the carriage, also act as a carriage retarding or controlling means to prevent the carriage from running with undue speed during tabulating operations, although said devices are normally disconnected from the 95 carriage and do not affect it during step-by-step feed thereof.

If it be desired to have the various lines of hyphens on the sheet all terminate at the same point, say at "60" of each line, and 100 so as to avoid any possibility of the hyphens running into the numeral or amounts column, a special tabulator stop 23 may be placed on the rack 22 at the point "60", so that when the two keys 30 and 4^a are held 105 down a line of hyphens other characters will be written and the carriage arrested at the point "60" of each line by the coöperation of a denominational stop 24 with the special stop 23 previously set at "60"; then, after 110 releasing the hyphen key and the key 30, the tabulator key 30 of the proper denomination will be depressed alone to bring the carriage to proper position for writing the first 115 numeral of the amount in its proper denominational position. In this use of the invention with the special stop 23 the decimal or any other selected denominational stop may be used in connection with the hyphen key to arrest the carriage at the point "60", or 120 other selected point, for positively stopping off the lines of hyphens uniformly on the sheet.

While in practice I prefer to place the 125 means for effecting an operative connection and disconnection between the carriage and the type bar vibrating device under control of a tabulator key, it should be understood that from certain aspects of my invention a key 30 may be an independent key discon- 130

nected from the associated denominational stop 24 and the universal bar and the key will be connected directly with the link 35 so that the function of the disconnected key 30 will be to render the actuating means effective or ineffective independently of tabulating operations. Moreover, it will be understood that various characters such as underscore marks, stars, dots, parentheses, periods, commas, etc., may be employed on the face of the type block on the type bar controlled by the reciprocating rod 56 and that the use of the mechanism may vary somewhat in accordance with the character employed.

Various changes may be made without departing from the spirit and scope of my invention.

What I claim as new and desire to secure 20 by Letters Patent, is:—

1. In a typewriting machine, the combination of a power driven carriage, escapement devices for the carriage, tabulating devices, a type carrier, actuating means for 25 operating said type carrier, said actuating means comprising a rotative device, and means for taking the carriage out of the control of the escapement devices and placing it under control of the tabulating devices and for simultaneously operatively connecting said rotative device to the carriage to be rotated thereby.

2. In a typewriting machine, the combination of a power driven carriage; escapement devices therefor; tabulating devices; a type bar; actuating means for intermittently operating the type bar during the travel of the carriage in the direction of its feed, said actuating means comprising a 40 normally inoperative rotative device; and means for taking the carriage out of control of said escapement devices and placing it under control of said tabulating devices and for simultaneously operatively connecting said rotative device with the carriage to be rotated thereby.

3. In a typewriting machine, the combination of a power driven carriage; escapement devices therefor; tabulating devices; a 50 type bar; actuating means for intermittently operating the type bar during the travel of the carriage in the direction of its feed, said actuating means comprising a normally inoperative rotative device; means for taking the carriage out of control of said escapement devices and placing it under control of said tabulating devices and for simultaneously operatively connecting said rotative device with the carriage to be rotated thereby; and key actuated means for placing the type bar under control of said rotative device.

4. In a typewriting machine, the combination of a power driven carriage; escapement devices therefor; tabulating devices; a 60

type bar; actuating means for intermittently operating the type bar during the travel of the carriage in the direction of its feed, said actuating means comprising a normally inoperative rotative device and a reciprocating device controlled by said rotative device; means for taking the carriage out of control of said escapement devices and placing it under control of said tabulating devices and for simultaneously operatively connecting said rotative device with the carriage to be rotated thereby; and key actuated means for moving the type bar into coöperative relation with said reciprocating device.

5. In a typewriting machine, the combination of a power driven carriage; a feed rack carried thereby; tabulating mechanism; a type bar; key actuated means for moving the type bar to printing position; actuating means for vibrating said type bar 25 when it is moved to printing position by said key, said actuating means comprising a rotative device; and means under control of said tabulating mechanism for effecting a geared connection between said feed rack 90 and said rotative device.

6. In a typewriting machine, the combination of a power driven carriage; a feed rack carried thereby; a type bar; actuating means for vibrating the type bar, said actuating means comprising a reciprocatory device and a rotative device for actuating it; key actuated means for moving the type bar into the path of said reciprocatory device; and means for releasing the carriage and 100 for simultaneously effecting a geared connection between said rotative device and said feed rack.

7. In a front strike typewriting machine, the combination of a power driven carriage, 105 an upwardly and rearwardly striking type bar, an actuating device that is adapted to be projected into the path of said type bar and to vibrate the same, a rotative device for operating said actuating device, and 110 means for effecting an operative connection and disconnection between said rotative device and the carriage.

8. In a front strike typewriting machine, the combination of a power driven carriage, 115 an upwardly and rearwardly striking type bar, an actuating device that is adapted to be projected into the path of said type bar and to vibrate the same, a rotative device for operating said actuating device, tabulating mechanism, and means controlled by said tabulating mechanism for effecting an operative connection and disconnection between said rotative device and the carriage.

9. In a typewriting machine, the combination of a carriage, a rack carried thereby, a type carrier, a pivoted support, a shaft carried by said support and adapted to turn thereon, a pinion carried by said shaft and adapted to be thrown into and out of mesh 130

with said feed rack, actuating means for vibrating said type carrier, and means for establishing an operative connection between said actuating means and said shaft when the pinion is thrown into mesh with said feed rack.

19. In a typewriting machine, the combination of a carriage, a rack carried thereby, a type carrier, a pivoted support, a shaft carried by said support and adapted to turn thereon, a pinion carried by said shaft and adapted to be thrown into and out of mesh with said feed rack, actuating means for vibrating said type carrier, tabulating mechanism, and means under control of said tabulating mechanism for establishing an operative connection between said shaft and said actuating means.

20. In a typewriting machine, the combination of a carriage, a rack carried thereby and movably mounted thereon, a feed pinion with which said rack coöperates, a type carrier, a pivoted support, a shaft carried by said support and adapted to turn thereon, a disengaging pinion carried by said shaft and adapted to be thrown into and out of mesh with said feed rack and to disengage the rack from the feed pinion, actuating means for vibrating said type carrier, and means for establishing an operative connection between said actuating means and said shaft when the disengaging pinion is thrown into mesh with and disengages said feed rack from the feed pinion.

25. 12. In a typewriting machine, the combination of a carriage, a rack carried thereby and movably mounted thereon, a feed pinion with which said rack coöperates, a type carrier, a pivoted support, a shaft carried by said support and adapted to turn thereon, a disengaging pinion carried by said shaft and adapted to be thrown into and out of mesh with said feed rack and to disengage the rack from the feed pinion, actuating means for vibrating said type carrier, tabulating mechanism, and means under control of said tabulating mechanism for establishing an operative connection between said shaft and said actuating means.

30. 13. In a typewriting machine, the combination of a power driven carriage; a feed rack carried thereby; a type carrier; a pivoted support; a shaft carried by said support and adapted to turn thereon; a pinion carried by said shaft; a gear likewise carried by the shaft; devices for actuating the type carrier, said actuating devices comprising a rotative device having a gear adapted to coöperate with the gear on said shaft; a key for moving said type carrier into cooperative relation with the said actuating devices, and key actuated means for turning said pivoted support to throw the pinion into mesh with the feed rack and to throw said gears into mesh.

35. 14. In a typewriting machine, the combination of a power driven carriage; a feed rack carried by and pivoted on the carriage; a feed pinion with which said rack meshes; a type carrier; a pivoted support; a shaft carried by said support and adapted to turn thereon; a disengaging pinion carried by said shaft; a gear likewise carried by the shaft; devices for actuating the type carrier, said actuating devices comprising a rotative device having a gear adapted to coöperate with the gear on said shaft; a key for moving said type carrier into coöperative relation with the said actuating devices; and key actuated means for turning said pivoted support to throw the disengaging pinion into mesh with the feed rack and move the feed rack out of engagement with the feed pinion and to throw said gears into mesh.

40. 15. In a typewriting machine, the combination of a power driven carriage; a feed rack carried thereby; a type carrier; a pivoted support; a shaft carried by said support and adapted to turn thereon; a pinion carried by said shaft; a gear likewise carried by the shaft; devices for actuating the type carrier, said actuating devices comprising a rotative device having a gear adapted to coöperate with the gear on said shaft; a key for moving said type carrier into coöperative relation with the said actuating devices; and key actuated means for turning said pivoted support to throw the pinion into mesh with the feed rack and to throw said gears into mesh.

45. 16. In a typewriting machine, the combination of a power driven carriage; a feed rack carried by and pivoted on the carriage; a feed pinion with which said rack meshes; a type carrier; a pivoted support; a shaft carried by said support and adapted to turn thereon; a disengaging pinion carried by said shaft; a gear likewise carried by the shaft; devices for actuating the type carrier, said actuating devices comprising a rotative device having a gear adapted to coöperate with the gear on said shaft; a key for moving said type carrier into coöperative relation with the said actuating devices; tabulating devices; and means controlled by said tabulating devices for turning said pivoted support to throw the pinion into mesh with the feed rack and to throw said gears into mesh.

50. 17. In a typewriting machine, the combination of a power driven carriage; a feed rack carried by and pivoted on the carriage; a feed pinion with which said rack meshes; a type carrier; a pivoted support; a shaft carried by said support and adapted to turn thereon; a disengaging pinion carried by said shaft; a gear likewise carried by the shaft; devices for actuating the type carrier, said actuating devices comprising a rotative device having a gear adapted to coöperate with the gear on said shaft; a key for moving said type carrier into coöperative relation with the said actuating devices; tabulator stops; a tabulator key for bringing said stops into coöperative relation; and means controlled by said tabulator key for turning said pivoted support to throw the disengaging pinion into mesh with the feed rack and move the feed rack out of engagement with the feed pinion and to throw said gears into mesh.

55. 18. In a front-strike typewriting machine, the combination of a power driven carriage; an upwardly and rearwardly striking type bar; and actuating means for vibrating said type bar, said vibrating means comprising

a rod that extends fore and aft of the machine and which is adapted to coöperate with said type bar when it is at or near the printing position, a rotative device for transmitting a longitudinal reciprocating movement to said rod, and means controlled by the power employed to move the carriage to rotate said rotative device.

18. In a front strike typewriting machine, the combination of a power driven carriage, an upwardly and rearwardly striking type bar; actuating means for vibrating said type bar, said actuating means comprising a rod that extends fore and aft of the machine and which is adapted to coöperate with said type bar when it is at or near the printing position, a rotative device for

transmitting a longitudinal reciprocating movement to said rod, and means controlled by the power employed to move the carriage to rotate said rotative device; tabulating mechanism; and means controlled by said tabulating mechanism for rendering the power employed to move the carriage effective or ineffective to actuate said rotative device. 20
